FIRE EXTINGUISHING PROCESS

Luis E. Eckelmann, Brooklyn, and George E. Ferguson, Spring Valley, N. Y., assignors to Pyrene Manufacturing Company, Newark, N. J., a corporation of Delaware

No Drawing. Application February 20, 1953,
Serial No. 338,132

3 Claims. (Cl. 169—1)

The present invention relates to a novel process for extinguishing dual fires involving both metals and organic chemicals, particularly organic liquid hydrocarbons.

It is an object of the present invention to provide a novel process for extinguishing dual or combined fires of combustible metals with those of inflammable organic chemicals in which the metal may be immersed or in contact with, which process is efficient, dependable and spectacular in its results, and which uses materials which may be easily stored and which produce no toxic by-products.

It is a further object of the invention to provide a simple process for extinguishing dual metal and solvent fires which requires a minimum of equipment and only inexpensive materials.

Other objects will be apparent to those skilled in the art after reading the specification which follows.

Fires caused by the combustion of metals, and particularly the light metals, have presented a problem in recent years due to greatly increased production of the light metals and their wide-spread commercial application. These light metals, which include sodium, lithium, potassium, magnesium and aluminum, burn with an intense, hot flame when ignited. Also, some of the heavier metals, such as iron and zinc, are prone to ignite and burn at a very high temperature. Most of the common fire-extinguishing materials are not satisfactory for treating the fires of the combustible metals, for most react violently with the hot, burning metal and only serve to spread the fire. Special methods and materials had to be designed to combat these fires.

A fire extinguishing problem which has to the present time defied a satisfactory solution, and which has become a problem of increasing importance to those charged with safety and fire extinguishing, is that involving a dual or combined fire of a metal and an inflammable organic chemical. It is believed apparent to those skilled in the art that the presence of the burning organic chemical greatly complicates and aggravates the problem of extinguishing the metal fire as well as presenting the problem of extinguishing the burning chemical.

It is a common practice to store turnings, filings, dust, as well as bars and other physical forms of metals, and particularly light metals, suspended or immersed in an organic chemical liquid. For example, powdered leaf aluminum is being used in ever increasing amounts as a pigment in aluminum paints. Aluminum powder, in its finely divided state, will dust into the air very readily and can ignite spontaneously in the air. It can also ignite spontaneously after being moistened with water. To overcome these fire dangers, and to aid in readily incorporating the aluminum powder into a paint vehicle, it is common practice to store the powder suspended in a liquid hydrocarbon organic material. The hydrocarbon liquid used in making this aluminum "paste" may be ligroin or V. M. P. naphtha (petroleum fractions having a boiling point between that of gasoline and kerosene), although other petroleum fractions may be used which

2

are compatible with the other paint ingredients. The amount of hydrocarbon used may be suitably varied, but it has been found convenient to use an amount of about 10% of the weight of the total aluminum "paste." Others of the light metals are often immersed in hydrocarbon liquids to prevent undue oxidation or other undesirable reactions from taking place. Thus sodium and potassium are frequently stored in an oil or hydrocarbon immersion.

While the storing of the combustible metals as an immersion in an organic liquid alleviates somewhat the incidence of fires of the combustible metals, it creates a fire hazard all of its own. The present invention provides a process for extinguishing dual fires of these compositions.

Our invention comprises a novel process for extinguishing dual fires of a combustible metal and an inflammable organic liquid, which comprises placing a liquid film of an aromatic ester of a phosphoric acid over the burning liquid and metal. The process is particularly applicable to dual fires of the powdered light metals, such as aluminum and magnesium, immersed in a liquid petroleum hydrocarbon, such as ligroin and naphtha. The process finds ready application in dual fires of combustible metals in any state of physical division, such as turnings, dust, powder, bars, etc., and including sodium, potassium, zinc, iron, lithium and zirconium in conjunction with organic liquids, particularly the petroleum hydrocarbons.

A single aromatic ester of a phosphorus acid may be used alone or in a mixture of various aromatic esters of a phosphorus acid. Among the esters contemplated for use in our process are the aromatic tri-esters of phosphoric acid, particularly such as tri-aryl phosphates as diphenyl-mono-(ortho-xenyl) phosphate, tri-(para-tertiary-butylphenyl) phosphate, di-(para-tertiary-butylphenyl)-mono-phenyl phosphate and (4-tertiary-butylphenyl) (phenyl) (ortho-xenyl) phosphate, or the aromatic tri-esters of phosphorus acid, such as di-(2-xenyl) phenyl phosphite, and such esters of thiophosphoric acid as phenyl di-(meta-tolyl) thiophosphate and diphenyl ortho-xenyl thiophosphate. It is essential to successful application of the process that the ester used be a liquid at the temperatures at which they will be stored in readiness for instant usage for extinguishing fires.

Of the aromatic esters of a phosphorus acid which have been tested to date, those of the tri-aryl phosphates have given best results. Diphenyl-mono-(ortho-xenyl) phosphate in particular has given spectacular results and appears to be ideally suited for use in our process in all respects. So satisfactory has the use of this ester been that we wish to particularly direct our process to the use of this ester.

In the application of our process to dual fires it is our purpose to provide a layer or film of the viscous liquid phosphorus acid aromatic esters over the surface of the burning composition. Best results are not obtained by spraying, sprinkling or squirting the ester over the surface of the burning composition. It is important not to break the surface of the burning liquid and this may easily happen if the ester is sprayed, sprinkled or squirted on. It is preferred that the masking of the burning liquid with the ester be effected by flowing the ester over the burning surface. Preferably the ester, which is a highly viscous liquid, is flowed out onto the surface of the burning composition much like syrup is poured over the surface of a pancake. This technique of application is a significant feature of our process and constitutes an important phase of our invention. One means for flowing the ester over the surface of the burning composition is to slowly pour the ester in a thin stream from a supply chamber over the side of the container holding the burning composition and onto the contents.

The storage vessel holding the ester should preferably be equipped with a delivery channel having a flow regulating means.

By practicing our process, dual fires of a burning metal and an organic liquid are easily and quickly extinguished with no flashback, reaction or sputtering as the aromatic ester of the phosphorus acid is applied. Also, no undesirable or even noticeable fumes are produced by the ester.

When the extinguishing fluid has been in contact with the hot liquid and metal for a short time, the viscosity of the fluid is reduced from a very thick consistency to a thin consistency approaching that of water. The resulting low viscosity extinguishing fluid is then in condition to penetrate the entire burning mass and by its cooling action, extinguishes the combustion.

In order to disclose more clearly the nature of the present invention, a specific example illustrating the process of the invention will hereinafter be described. This is done solely by way of example and is intended neither to delineate the scope of the invention nor limit the ambit of the appended claims.

In a test demonstration, an open steel tank 4 ft. x 8 ft. x 4 in. was filled with about 100 lbs. of a powdered aluminum paste containing about 10% by weight of naphtha. Over one end of the tank was installed a two inch pipe leading to a drum of diphenyl-mono-(ortho-xenyl) phosphate. The pipe was equipped with a quick-opening knife valve. The powdered aluminum paste was ignited and permitted to burn for 10 minutes, during which time the metal had become involved in several very hot fires. The extinguishing fluid was slowly released and permitted to flow gently until it covered the burning surface. Within about 2 or 3 minutes all of the fires had been completely extinguished without any sputtering or evolution of any undesirable or noticeable fumes. These test conditions are believed to parallel field conditions and present the severest test conditions available. The results show that the process provides a

satisfactory solution to the problem presented by dual metal and hydrocarbon fires.

The terms and expressions which we have employed are used as terms of description and not of limitation, and we have no intention, in the use of such terms and expressions, of excluding any equivalents of the features shown and described or portions thereof, but recognize that various modifications are possible within the scope of the invention claimed.

What is claimed is:

1. A process for extinguishing dual fires of a finely divided combustible light metal and a liquid petroleum hydrocarbon which comprises pouring a layer of an aromatic tri-ester of phosphoric acid over the surface of the burning composition with the use of only such force as will spread the phosphoric acid ester over the surface of the burning composition without substantially penetrating the surface.
2. A process for extinguishing dual fires of a finely divided light metal selected from the class consisting of aluminum and magnesium and a liquid petroleum hydrocarbon which comprises pouring a layer of diphenyl-mono-(ortho-xenyl) phosphate over the surface of the burning composition with the use of only such force as will spread said phosphate over the surface of the burning composition without substantially penetrating the surface.
3. A process for extinguishing dual fires of a paste of powdered aluminum and naphtha; said naphtha comprising about 10% of the weight of the paste, which comprises pouring a layer of diphenyl-mono-(ortho-xenyl) phosphate over the surface of the burning aluminum paste with the use of only such force as will spread said phosphate over the surface of the burning aluminum paste without substantially penetrating its surface.
